ALKYLATION

Ludwig Kniel, Jackson Heights, N. Y., assignor to
The Lummus Company, New York, N. Y., a corporation of Delaware

Application April 29, 1942, Serial No. 440,930

6 Claims. (Cl. 260—683.4)

The present invention relates to improvements in the alkylation of isoparaffinic hydrocarbons with olefinic hydrocarbons to form hydrocarbons boiling within the range of gasoline and particularly suitable for use as a high antiknock aviation grade motor fuel.

In the alkylation of an isoparaffin with an olefin in the presence of a suitable alkylation catalyst to form high antiknock predominantly isoparaffinic gasoline hydrocarbons, a considerable problem is generally presented in the elimination of hydrocarbons lower boiling than the isoparaffinic reactant from the alkylation system, particularly in the separation of the hydrocarbon mixture discharged from the alkylation zone for the recovery of the desired alkylate. This problem primarily involves fractionation difficulties in the handling of relatively large amounts of reactants and unreactive materials utilized in the formation of a relatively small amount of desired alkylate with the consequent large equipment required to accomplish the necessary fractionation.

Since it is necessary to have the isoparaffinic reactant, e. g., isobutane, present in an amount in substantial excess of that required to react with the olefinic reactant, e. g., a butene in the alkylation zone in order to obtain a substantial degree of alkylation, it becomes desirable from an economic viewpoint to recycle the excess isoparaffinic reactant separated from the alkylate to the alkylation zone to maintain the desired ratio of isoparaffin to olefin therein. At the same time, however, the recycling of hydrocarbons lower boiling than the isoparaffinic reactant, e. g., propane, which is invariably introduced into the alkylation system along with the C₄ fraction containing the isobutane and/or the butene, is to be avoided as much as possible since, for optimum operation, it is necessary to maintain a substantially low concentration of propane in the alkylation zone.

Accordingly, it is an object of my invention to provide an improved method of fractionating the hydrocarbon mixture discharged from the alkylation zone in an isoparaffin-olefin alkylation system whereby a material saving in equipment and operating costs can be effected.

It is a further object of my invention to provide an improved method of separating the isobutane and the propane from the hydrocarbon mixture discharged from the alkylation zone in an isobutane-butene alkylation system for recycling of the isobutane to the alkylation zone and elimination of the propane from the alkylation system.

Another object of my invention is to provide a relatively simple procedure for the elimination of propane from an isobutane-butene alkylation system without the use of excessive fractionating

equipment and with substantially no loss of isobutane.

Further objects and advantages of my invention will be apparent from the following description of a preferred form of embodiment thereof taken in connection with the accompanying drawing, which represents a typical flow sheet of a process embodying my invention.

For convenience only, my invention will be described in connection with the alkylation of isobutane with a butene in the presence of concentrated sulfuric acid to form high antiknock gasoline containing a major proportion of isooctanes. It will be appreciated, however, that my invention is not so restricted but is applicable to the alkylation of any isoparaffin with any olefin, whether such materials are normally gaseous or not, in the presence of any suitable alkylation catalyst to form predominantly isoparaffinic hydrocarbons suitable for use as a high antiknock motor fuel.

According to my invention, a butane-butene feed containing isobutane and butenes and also containing propane unavoidably admixed therewith is passed to an alkylation zone wherein the isobutane, maintained in excess of that required to react with the butenes, is alkylated with the butenes in the presence of concentrated sulfuric acid to form high antiknock hydrocarbons boiling within the range of gasoline. The resulting alkylate product is separated from the acid and is neutralized, and the excess isobutane and lower boiling hydrocarbons including propane are separated as overhead from the alkylate, from which the desired gasoline fraction is recovered. The isobutane overhead is subjected to a progressive partial condensation to form a plurality of partial condensates consisting primarily of the isobutane to be recycled and a final condensate containing propane in a greater concentration than the isobutane overhead whereby the propane is concentrated in a stream of relatively small volume at a point in the alkylation system where it can be most readily eliminated therefrom by fractionation. The isobutane contained in the final condensate is recovered and is recycled to the alkylation zone.

In the operation of my invention, a butane-butene feed is supplied through line 1 to an alkylation reactor or chamber 3 wherein alkylation of the isobutane with the butenes is effected in the presence of concentrated sulfuric acid. The butane-butene feed comprises C₄ gaseous hydrocarbons primarily and may be derived from any suitable source, e. g., the overhead from the stabilization of natural gasoline, cracked naphtha, or the like. Preferably, this C₄ fraction has been subjected to a prior depropanizing step to eliminate the greater proportion of the C₃ hydrocarbons present in the overhead.

The molal ratio of the isobutane to the butenes introduced into reactor 3 should be at least 1:1 and preferably within the range of 2:1 to 10:1 since it is necessary to maintain an excess of isobutane over that required to react with the butenes during the alkylation reaction in order to accomplish a substantial degree of alkylation. Ordinarily, the butane-butene feed charged to the alkylation system will not contain sufficient isobutane to provide the desired excess as well as that necessary for the alkylation reaction. This deficiency can be made up by introducing further isobutane from an extraneous source as through line 4 and/or by recycling the excess isobutane in the system.

In reactor 3, the isobutane and the butenes are brought into intimate contact with each other and with the sulfuric acid to effect the desired alkylation. This sulfuric acid, which acts as a catalyst for the alkylation reaction, should have a concentration of between 90 to 100% and preferably of about 95 to 98%. The acid is supplied to reactor 3 through line 5. The pressure within the reactor should be sufficient to maintain the isobutane and the butenes in liquid condition at the particular reaction temperature, which should be in the range of 0 to 100° F. and preferably within the range of 40 to 60° F. The ratio of acid to hydrocarbons is desirably maintained within the range of $\frac{1}{2}$ to $1\frac{1}{2}$ volumes of acid per volume of hydrocarbon feed to the reactor.

Reactor 3 is desirably provided with an agitating or stirring mechanism 6 to provide the necessary intimacy of mixing. Any mixing device which provides a sufficient degree of agitation is suitable. The isobutane-butene mixture is maintained in reactor 3 for sufficient time to effect substantial alkylation of the isobutane with the butenes. Substantially complete consumption of the butenes can be effected under the proper alkylation conditions, which are well known to the art.

The acid-hydrocarbon mixture is continuously withdrawn from reactor 3 through line 7 and is passed into settling chamber 8, wherein it separates into an upper hydrocarbon layer and a lower acid layer. This lower layer comprising used acid is withdrawn from the settler through line 10, and a major portion thereof is preferably recycled through lines 11 and 5 to reactor 3 to be used in the alkylation of additional isobutane with butenes. A portion of the used sulfuric acid from settler 8 is desirably continuously discharged from the system through line 12, and fresh make-up sulfuric acid is continuously introduced into the system through line 13.

The upper hydrocarbon layer is withdrawn from settler 8 through line 14 and is passed into neutralizer 15, wherein the hydrocarbon mixture is treated with a neutralizing agent to neutralize the acidity of the hydrocarbons resulting from the contact thereof with the acid in reactor 3. A suitable neutralizing agent comprises an alkaline solution such as a dilute aqueous caustic soda solution, which may be introduced into the neutralizer through line 17. The alkaline solution separates out in the bottom of neutralizer 15 and is continuously withdrawn therefrom through line 19.

According to my invention, the neutralized hydrocarbon mixture is withdrawn from the top of neutralizer 15 through line 21 and is passed into debutanizer tower 23. This hydrocarbon mixture comprises the alkylate formed in reactor 3,

the excess isobutane, the normal butane introduced into the system along with the isobutane and the butenes, and any propane unavoidably admixed therewith. In tower 23 the hydrocarbon mixture is fractionated to separate the normal butane, the isobutane, and the lower boiling hydrocarbons including the propane from the alkylate, which is removed as a bottoms stream through line 25. The fractionating conditions in tower 23 may be so adjusted that a sufficient amount of normal butane is retained in the bottoms alkylate stream to give the resulting high antiknock gasoline product the particular volatility desired.

This bottoms stream is passed through line 25 into alkylate fractionator 27, wherein the gasoline boiling range constituents are separated from the heavier alkylate, which is removed from the system through bottoms line 29 for disposal as desired. The alkylate gasoline fraction is removed overhead in line 31 for condensation in condenser 33. A portion of the resulting condensate is returned through line 35 to tower 27 to serve as reflux. The remainder of the condensate is withdrawn from the system through line 37 and comprises the high antiknock aviation grade gasoline product.

Further in accordance with my invention, the normal butane, the isobutane, and the propane separated in debutanizer 23 are removed therefrom as an overhead stream through line 38. The primary feature of my invention comprises subjecting this overhead to a progressive partial condensation to form a plurality of partial condensates which contain the major portion of the isobutane to be recycled as well as the normal butane and some propane and a final condensate which contains the major portion of the propane to be eliminated from the system as well as some isobutane. The purpose of this progressive condensation operation is to concentrate the propane in a stream of relatively small volume at a point in the alkylation system where it can be most readily eliminated therefrom by fractionation.

Accordingly, the overhead vapors in line 38 are subjected to a partial condensation in condenser 39. The resulting condensate, which consists primarily of normal butane and isobutane, is collected in accumulator 40, and a portion of the condensate is returned to tower 23 through line 41 as reflux. The remainder of the condensate is passed through line 43 to deisobutanizer tower 45 for separation of the isobutane from the normal butane.

The uncondensed portion of the overhead from debutanizer tower 23, after separation from the condensate in accumulator 40, is passed through line 47 for condensation in condenser 49, wherein it is subjected to a final condensation which substantially completely condenses the remaining vapors. The resulting condensate is desirably collected in a surge tank or accumulator 50, from which it is passed to depropanizer tower 51 through line 53.

It will be appreciated that any number of partial condensation stages may be employed to accomplish the object of concentrating the undesirable propane in a stream of relatively small volume so that it can be more readily eliminated from the alkylation system. Only two condensation stages have been shown here for purposes of simplicity in order to bring out this primary feature of my invention.

The feed to depropanizer 51 comprises the major portion of the propane in the overhead from

debutanizer 23 as well as some isobutane and a small amount of normal butane. In depropanizer 51 the propane is separated from the isobutane, which is removed as a bottoms stream through line 55 and is passed through line 43 to deisobutanizer 45 for separation and elimination of any normal butane admixed therewith. If desired, a part of the propane condensate from surge tank 50 may be passed directly to line 43 through line 56 according to the amount of propane to be eliminated from the system.

The overhead from depropanizer 51 comprises substantially only propane and is removed through line 57 for condensation in condenser 59. The resulting condensate is passed by line 61 to accumulator 63, from which it is passed through line 65 to depropanizer 51 as reflux. Condenser 59 is operated under conditions whereby only the necessary reflux condensate for tower 51 is condensed. Accordingly, the uncondensed propane is eliminated from the system as through the valved vent line 67. Any loss of isobutane carried off with the eliminated propane is reduced to a substantially negligible minimum through this operation.

In deisobutanizer 45 the isobutane is separated from the normal butane, which is removed from the system through the bottoms line 69. The overhead stream containing the excess isobutane and any propane present in the partial condensate produced by condenser 39 is removed through line 71 for condensation in condenser 73. The resulting condensate is collected in accumulator 75, from which a sufficient portion of the condensate is returned through line 79 to tower 45 as reflux. The remainder of the condensate comprising the excess isobutane required in the reactor 3 is recycled through line 81 for use in the alkylation of further isobutane with butenes.

It is generally desirable to maintain the percentage of propane in the alkylation zone below 3% by weight because the propane is inert as far as the alkylation reaction is concerned and because it also adversely affects the yield of alkylate if it is present in too great a proportion during alkylation. Accordingly, unless the propane is continuously vented or eliminated from the alkylation system in some fashion, it will continuously be recycled along with the excess isobutane and will gradually accumulate in the system and thereby adversely affect the alkylation reaction. It should be noted that the amount of propane that must be vented from the system controls all of the fractionating operations prior to this point.

In a particular application of my invention, the hydrocarbon effluent from reactor 3 was 345,500 lbs. per day, of which propane comprised 10,300 lbs. per day or 3% by weight. This effluent was debutanized in tower 23, the overhead from which was 240,000 lbs. per day and contained all of the propane as well as substantially all of the isobutane and normal butane in the hydrocarbon effluent. The concentration of propane in this overhead stream was thus increased to 4.3% by weight by removal of the alkylate. The partial condensate from condenser 39 contained 50% of the propane, 65% of the isobutane, and 70% of the normal butane in the debutanizer overhead. The uncondensed portion of this overhead was 82,100 lbs. per day, of which propane comprised 5,300 lbs. per day or 6.45% by weight. By means of this partial condensation procedure, the propane to be eliminated from the system was concentrated in a stream of considerably smaller quantity than that of the

hydrocarbon effluent. This uncondensed portion was substantially completely condensed in condenser 49 and was fractionated in depropanizer 51 with 4,970 lbs. per day of propane being eliminated from the system through vent line 67. This material vented through line 67 also contained 300 lbs. per day of isobutane. This represents approximately 0.1% by weight of the isobutane content of the hydrocarbon effluent and constitutes practically a negligible daily loss of isobutane.

Several advantages flow from this procedure of increasing the propane concentration in the stream from which propane is to be eliminated. Concentration of propane reduces the charge to the depropanizer tower whereby a tower of smaller diameter and height can be employed: the charge contains a greater concentration of propane, and, hence, the amount of charge is less. Concentration of propane also reduces the reflux ratio required in the depropanizer with a corresponding reduction in the amount of cooling required and in the tower size because of the smaller amount of material being treated whereby less reflux is needed. Concentration of propane further effects a reduction in the number of plates required in the stripping section of the depropanizer tower to produce a bottoms stream of a predetermined composition because of the smaller amount of material to be treated. In many cases, the size of the depropanizer tower may thus be reduced to approximately $\frac{1}{2}$ of the tower size required for the removal of propane without preconcentration of the propane-containing stream.

It will be appreciated that my invention is not necessarily limited to the use of concentrated sulfuric acid as the alkylation catalyst. Other suitable substances for effecting this alkylation comprise aluminum chloride, phosphoric acid, hydrofluoric acid, and the like.

Although I have described a preferred form of embodiment of my invention, I am aware that modifications may be made thereto; therefore, only such limitations as appear in the claims appended hereinafter should be made.

I claim:

1. The process of alkylating an isoparaffin with an olefin to form high antiknock motor fuel, said isoparaffin containing lower boiling unreactive hydrocarbons unavoidably admixed therewith, which comprises contacting the isoparaffin and the olefin in an alkylation zone with an alkylation catalyst to effect alkylation of the isoparaffin with the olefin, maintaining an excess of isoparaffin over that required to react with the olefin during alkylation, separating the resulting hydrocarbon mixture from the alkylation catalyst, fractionating the hydrocarbon mixture to separate the unreacted hydrocarbons as overhead from the alkylate, partially condensing said overhead to produce a condensate containing primarily unreacted isoparaffin and to concentrate the major portion of the lower boiling unreactive hydrocarbons in the uncondensed portion of the overhead, separating the uncondensed portion of said overhead and subjecting it to further fractionation within a zone independent of the zone of said first fractionation for control of fractionating conditions independently of fractionating conditions within said first zone to separate the lower boiling hydrocarbons from a bottoms fraction containing isoparaffin therein, eliminating the separated lower boiling hydrocarbons from the system, recovering unreacted isoparaffin from

said condensate and said bottoms fraction and recycling it to the alkylation zone to maintain said excess of isoparaffin therein, and fractionating the alkylate to recover a high antiknock motor fuel.

2. In the process of alkylating an isoparaffin with an olefin to form high antiknock motor fuel in the presence of an alkylation catalyst wherein the isoparaffin is present in excess of that required to react with the olefin and wherein unreactive hydrocarbons both higher boiling and lower boiling than the isoparaffin are also present, the improvement which comprises fractionating the hydrocarbon effluent from the alkylation zone consisting of alkylate and unreacted hydrocarbons to separate the unreacted hydrocarbons as overhead from the alkylate, progressively condensing said overhead in a series of partial condensation stages to produce a plurality of condensates containing primarily unreacted isoparaffin and higher boiling unreactive hydrocarbons and to concentrate the greater portion of the lower boiling unreactive hydrocarbons in the uncondensed portion of the overhead, condensing the final uncondensed portion of the overhead, fractionating the resulting final condensate within a zone independent of the zone of said first fractionation for control of fractionating conditions independently of fractionating conditions within said first zone, to separate the unreactive lower boiling hydrocarbons from a bottoms fraction containing unreacted isoparaffin therein, eliminating the separated lower boiling hydrocarbons from the system, recovering unreacted isoparaffin from said condensates and from said bottoms fraction and recycling it to the alkylation zone to maintain said excess of isoparaffin therein, and fractionating the alkylate to recover a high antiknock motor fuel.

3. The process of alkylating isobutane containing admixed propane with a normally gaseous olefin to form high antiknock motor fuel, which comprises contacting the isobutane and the olefin with concentrated sulfuric acid in an alkylation zone to effect alkylation of the isobutane with the olefin, maintaining an excess of isobutane over that required to react with the olefin during alkylation, separating the resulting hydrocarbon mixture from the sulfuric acid, fractionating the hydrocarbon mixture to separate the unreacted hydrocarbons as overhead from the alkylate, partially condensing said overhead to form a condensate containing primarily unreacted isoparaffin and to concentrate the greater portion of the propane in the uncondensed portion of the overhead, separating such uncondensed portion of the overhead and condensing it, fractionating the resulting final condensate within a zone independent of the zone of said first fractionation, for control of fractionating conditions independently of fractionating conditions in said first zone, to separate the propane from a bottoms fraction containing isobutane therein, eliminating the separated propane from the system, recovering isobutane from said condensate and from said bottoms fraction and recycling it to the alkylation zone to maintain the excess of isobutane therein, and fractionating the alkylate to recover a high antiknock motor fuel.

4. The process of alkylating isobutane with a butene to form high antiknock motor fuel, said reactants containing normal butane and lower

boiling hydrocarbons including propane admixed therewith, which comprises contacting the isobutane and the butene with concentrated sulfuric acid in an alkylation zone to effect alkylation of the isobutane with the butene, maintaining an excess of isobutane over that required to react with the butene during alkylation, separating the resulting hydrocarbon mixture from the sulfuric acid, fractionating the hydrocarbon mixture to separate unreacted hydrocarbons as overhead from the alkylate, partially condensing said overhead to form a condensate containing primarily normal butane and isobutane and to concentrate the major portion of the propane in the uncondensed portion of the overhead, separating such uncondensed portion of the overhead and condensing it, fractionating the resulting final condensate within a zone independent of the zone of said first fractionation, for control of fractionating conditions independently of fractionating conditions in said first zone to separate the propane and lower boiling hydrocarbons from isobutane and normal butane contained therein, eliminating the separated propane from the system, further separating the isobutane from the normal butane, collecting the separated isobutane and recycling it to the alkylation zone to maintain the excess of isobutane therein, and fractionating the alkylate to recover a high antiknock motor fuel.

5. The process as claimed in claim 4, wherein the concentration of propane in the alkylation zone is maintained below 3% by weight.

6. The process of alkylating an isoparaffin with an olefin to form high antiknock motor fuel, said reactants containing lower boiling unreactive hydrocarbons unavoidably admixed therewith, which comprises contacting the isoparaffin and the olefin with an alkylation catalyst to effect alkylation of the isoparaffin with the olefin, maintaining an excess of isoparaffin over that required to react with the olefin during alkylation, separating the resulting hydrocarbon mixture from the alkylation catalyst, fractionating the hydrocarbon mixture to separate the unreacted hydrocarbons as overhead from the alkylate, partially condensing said overhead to produce a condensate containing primarily unreacted isoparaffin and to concentrate the major portion of the lower boiling unreactive hydrocarbons in the uncondensed portion of the overhead, separating the uncondensed portion of said overhead and subjecting it to further fractionation within a zone independent of the zone of said first fractionation for control of fractionating conditions independently of fractionating conditions within the zone of said first fractionation, to separate the lower boiling hydrocarbons from a bottoms fraction containing isoparaffin therein, eliminating the separated lower boiling hydrocarbons from the system, passing said bottoms fraction to a third fractionation zone independent of said other fractionation zones, passing to said third zone, independently of said second zone the isoparaffin and another portion of said lower boiling unreactive hydrocarbon obtained from said first fractionation, for recovery of the isoparaffin as overhead from the third zone, recycling the recovered isoparaffin to the alkylation zone, and fractionating the alkylate to recover a high antiknock motor fuel.

LUDWIG KNIEL.
